DESIGN FOR A LAMP CASING

Louis Z. La Forest, Orange, N. J., assignor to
Thomas A. Edison, Incorporated, West Orange,
N. J., a corporation of New Jersey

Application April 26, 1939, Serial No. 84,579

Term of patent 14 years

To all whom it may concern:

Be it known that I, Louis Z. La Forest, a citizen of the United States, residing at Orange, in the county of Essex and State of New Jersey, have invented a new, original, and ornamental Design for a Lamp Casing, of which the following is a specification, reference being had to the accompanying drawing, forming a part thereof.

Fig. 1 is a view in side elevation of a lamp casing, showing my new design;

Fig. 2 is a top plan view of the lamp casing shown in Fig. 1;

Fig. 3 is a view in rear elevation of the lamp casing shown in Fig. 1; and

Fig. 4 is a view in front elevation of the lamp casing shown in Fig. 1.

I claim:

The ornamental design for a lamp casing, as shown.

LOUIS Z. LA FOREST.
